C. G. JOHNSON

DIE AND CUTTER

Filed June 13, 1922

Inventor
Charles G. Jaleensus
By George E. Taylor
Atty.

UNITED STATES PATENT OFFICE.

CHARLES G. JOHNSON, OF WORCESTER, MASSACHUSETTS.

DIE AND CUTTER.

Application filed June 13, 1922. Serial No. 568,015.

To all whom it may concern:

Be it known that I, CHARLES G. JOHNSON, a citizen of the United States, residing at Worcester, in the county of Worcester and

5 State of Massachusetts, have invented certain new and useful Improvements in Dies and Cutters, of which the following is a specification, reference being had therein to the accompanying drawings.

10 This invention relates to a combined die and cutter, its principal object being to provide means for threading and otherwise cutting an article at one and the same operation.

15 Among other aims and objects of the invention may be recited the provision of a device of the character mentioned with a view to compactness, in which the number of parts are few, the construction simple, cost 20 of production small and efficiency and operation high.

The improvements in the details and arrangement of parts will be apparent from an inspection of the accompanying drawings, 25 in connection with the description hereinafter contained and wherein a preferred embodiment of the invention is disclosed for the purpose of imparting an understanding of the same.

30 Referring to the drawings in which like characters of reference indicate corresponding parts in the several views;

Figure 1 is an elevation of my improved die and cutter, partly in section;

35 Figure 2 is another elevation thereof, the parts in section being taken generally upon line 2-2 of Figure 1;

Figure 3 is a transverse sectional elevation, taken generally upon line 3-3 of 40 Figure 2;

Figure 4 is a view of the cutter; and

Figure 5 is an elevation, partly in section, of one form of article produced by my improved mechanism.

45 The form of article illustrated in Figure 5 is a metal cap that is formed either by casting, spinning, drawing or other means, and completed by my improved die and cutter by threading the exterior thereof, cutting the groove 24 around the outside thereof at least as deep, preferably slightly deeper, than the bottom of the threads, trimming the outer end and chamfering the outside near the outer end by removing one 50 or more of the threads.

Heretofore with an article of this character the operations have been successively performed by tools of different forms and structure, necessitating the securing of the article for each of the tools, then removing 60 it and after the operation again securing it for the next succeeding operation, etc.

In my invention I have provided a simple and effective device that performs all of these requisite operations with the same tool 65 while the article is secured but once in a holding device, instead of a plurality of times as heretofore. In these and other ways with my improved mechanism the objections heretofore found in the prior art 70 have been entirely eliminated.

In the drawings, 10 designates the die holder having a shank 11 and a chamber 12 therein. Secured in the open end of this die holder by screws 13, or the like, is the die 75 14 having a plurality of flutes 15 between the cutting portions 16.

In the bottom of the chamber 12 is a wedge ring 17 which supports two wedges 18 located diametrically opposite to each 80 other. The back of these wedges is substantially the same shape in cross-section as the flutes 15 so that the same may be readily supported therein, and the beveled inner face 19 has a tongue 20 thereon. These 85 wedges are secured against rotation by the keys 38, or the like, and their beveled faces 19 incline outwardly from the wedge ring 17. Slidable upon said wedges are the cutters 21, each of which has a groove 22 in its rear face for engagement with the said tongue 20. Each of these cutters is provided 90 with a lip 23 of substantially the same width as the groove 24 in the outside of the article to be operated upon and herein designated 25, 95 also a lip 26 to form the chamfer at 27 by removing one or more of the threads and also a cutting edge 28 to trim up slightly the outer end of the article. These cutters are moved endwise as a unit relatively to 100 the die holder, as well as being retained in a proper position relatively to each other by means of a stop collar 29 having a flange 30 thereon which enters a groove 31, in each of said cutters. The outer end of this stop 105 collar is in substantially the same plane as the outer end of said cutters.

Threaded in the die holder 10 and passing through the bushing 32 mounted in the ring 17 is a screw 33, the head of which is within 110

the bore 34 of said collar and concentric with the axis thereof, thus providing a guide and support for said collar.

Between the stop collar 29 and the ring 17 is a coil spring 35 which exerts its tension so as to keep the stop collar in its outermost position, substantially as shown in Figure 2.

In operation the article 25 outlined in Figure 2 by broken lines, is securely held in 10 any convenient manner, after which the tool with its parts substantially as shown in Figure 2 is positioned relatively thereto, the cutters being upon the outside thereof with their outer ends adjacent to the underside 15 of the bead 36, at which time the outer end of the stop collar 29 is in contact with the inner face of the head of said article.

The die holder 10, which is of course continually rotating, as it moves forward carries 20 with it the die 14 and cuts the thread 37 upon the outside thereof. As the die advances the cutters are moved inwardly by reason of their contact with the wedges 18 and perform their respective operations, that 25 is, cut the groove 24, square the outer end of the article and chamfer the edge adjacent thereto. When the die has reached its outer limit, the cutters have reached their innermost positions.

30 As the die is withdrawn the cutters move outwardly until they are entirely free from the article, which in its then finished position is easily removed, a new article substituted and operations continued as before.

35 Minor changes and alterations may be made within my invention, aside from those herein suggested, and I would therefore have it understood that I do not limit myself to the exact construction herein shown 40 and described, but claim all that falls fairly within the spirit and scope of the appended claims.

What I claim as new and desire to secure by Letters Patent, is:

45 1. In a device of the character described; a die; a cutter connected therewith; and means for moving said cutter radially relatively to said die during the operation of the die.

50 2. In a device of the character described; a die; a cutter connected therewith; means for moving the cutter radially relatively to the die during the operation of the die; and means for moving the cutter parallel with the axis of the die.

55 3. In a device of the character described; a die; a cutter connected therewith; means for moving the cutter radially relatively to the die during the operation of the die; and 60 yielding means for moving the cutter parallel to the axis of the die.

4. In a device of the character described; a die; a cutter connected therewith; means for moving the cutter radially relatively to the die during the operation of the die;

yielding means for moving the cutter parallel to the axis of the die; and means for limiting said parallel movement.

5. In a device of the character described; a die; a cutter connected therewith; and 70 means for moving said cutter radially relatively to said die, comprising inclined planes held in a fixed position relatively to said die.

6. In a device of the character described, 75 a die; a plurality of inclined planes connected therewith and lying within the flutes of said die; a plurality of cutters corresponding in number with said planes; and means for moving said cutters parallel to the axis of said die.

7. In a device of the character described, 85 a die; a plurality of inclined planes connected therewith and lying within the flutes of said die; a plurality of cutters corresponding in number with said planes; means for moving said cutters parallel to the axis of said die; and means for supporting said cutters, upon which the same are radially movable.

8. In a device of the character described, 90 a die; a plurality of inclined planes connected therewith and lying within the flutes of said die; a plurality of cutters corresponding in number with said planes; means for moving said cutters parallel to the axis of said die; means for supporting said cutters, upon which the same are radially movable; and means for limiting the axial movement of said cutters.

9. In a device of the character described, 95 a die holder; a die within said holder; a plurality of wedges lying within the flutes of said die and held in a fixed position relatively to said holder; a cutter slidably mounted upon each of said wedges; and means for limiting the endwise position of said cutters relatively to said wedges.

10. In a device for threading the exterior 110 of an article and cutting a groove around the outside thereof adjacent to the threaded portion; a die; a cutter movably connected therewith; and means actuated by the movement of the die for moving said cutter radially relatively to said die so that said cutter will project inwardly beyond the threaded portion thereof.

11. In a device for threading the exterior 115 of an article and cutting a groove around the outside thereof adjacent to the threaded portion; a die; a cutter movably connected therewith; and means actuated by the movement of the die for moving said cutter radially relatively to said die so that said cutter will project inwardly beyond the threaded portion thereof; and means for mounting said cutter upon said die so that the same may rotate therewith and move outwardly relatively thereto while the die is moving parallel to its axis.

12. In a device for threading the exterior of an article and cutting a groove around the outside thereof adjacent to the threaded portion, and trimming the outer end thereof; a die; a cutter movably connected therewith for performing both the grooving and trimming operations; and means for moving said cutter radially relatively to said die so that said cutter will extend 10 inwardly inside of the threaded portion thereof.

13. In a device for threading the exterior of an article and cutting a groove in the wall thereof adjacent to the threaded portion, trimming and chamfering the outer end thereof; a die; a single cutter for cutting said groove, and trimming and chamfering the article, movably connected with the die; and means for moving said cutter 20 radially relatively to said die so that said cutter will be inside of the threaded portion thereof.

14. In a device of the character described, a die; a plurality of inclined planes connected therewith and lying within the flutes of said die; a plurality of cutters corresponding in number with said planes; means for moving said cutters parallel to the axis of said die; means for supporting 25 said cutters, upon which the same are radially movable; and means for limiting the endwise position of said cutters relatively to said die.

15. In a device of the character described, a die; a plurality of inclined planes connected therewith and lying within the flutes of said die; a plurality of cutters corresponding in number with said planes; means for moving said cutters parallel to the axis 30 of said die; means for supporting said cutters, upon which the same are radially movable; and means for limiting the endwise position of said cutters relatively to

said die, and comprising a part fixed relatively to said supporting means and contacting therewith when said supporting means is in its extreme outer position. 45

16. In a device of the character described, a die holder; a die; a removable member in said die holder; a plurality of wedges connected with said member and projecting through the flutes of said die; and a cutter having a slidable contact with each of said wedges. 50

17. In a device of the character described, a die holder; a die; a removable member in said die holder; a plurality of wedges connected with said ring and projecting through the flutes of said die; a cutter having a slidable contact with each of said 55 wedges; and a member movable relatively to said die and having contact with each of said cutters. 60

18. In a device of the character described, a die holder; a die; a removable member in said die holder; a plurality of wedges connected with said ring and projecting through the flutes of said die; a cutter having a slidable contact with each of said 65 wedges; and a member movable relatively to said die and having contact with each of said cutters; and yielding means, for moving said latter member in one of its directions. 70

19. In a device of the character described, a die holder; a die; a removable member in said die holder; a plurality of wedges connected with said member and projecting through the flutes of said die; a cutter having a slidable contact with each of said 75 wedges; and a flanged member the flange of which has contact with all of said cutters. 80

In testimony whereof, I have hereunto affixed my signature.

CHARLES G. JOHNSON.
